(57) **CLAIM**

The ornamental design for a spa frame as shown and described.

DESCRIPTION

FIG. 1 is a front, top, and right side perspective view of a first embodiment of a spa frame.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, bottom, and left side perspective view thereof.

FIG. 9 is a front, top, and right side perspective view of a second embodiment of a spa frame.

FIG. 10 is a front view thereof.

FIG. 11 is a rear view thereof.

FIG. 12 is a left side view thereof.

FIG. 13 is a right side view thereof.

FIG. 14 is a top view thereof.

FIG. 15 is a bottom view thereof; and,

FIG. 16 is a rear, bottom, and left side perspective view thereof.

The dashed lines in the drawings depict portions of the spa frame that form no part of the claimed design.

Dash-dot broken lines in FIGS. 9-16 depict symbolic break lines. The symbolic break lines and any portions of the article between the break lines form no part of the claimed design.

The bracket lines and the areas between the symbolic breaks form no part of the claimed design.

1 Claim, 12 Drawing Sheets
